UNITED STATES PATENT OFFICE.

KILIAN ARNOLD, OF BROOKLYN, AND JOHN J. GERBER, OF JAMAICA, N. Y.

ZITHER.

SPECIFICATION forming part of Letters Patent No. 315,376, dated April 7, 1885.

Application filed August 21, 1884. (No model.)

To all whom it may concern:

Be it known that we, KILIAN ARNOLD, a citizen of the United States, residing at Brooklyn, in the county of Kings and State of New York, and JOHN J. GERBER, a citizen of the German Empire, residing at Jamaica, in the county of Queens and State of New York, have invented new and useful Improvements in Zithers, of which the following is a specification.

This invention relates to improvements in musical instruments known as "zithers;" and it consists in the combination, with the leading-strings, the pitches of which are changed by fingering in the usual manner, of accompanying - strings, the pitches of which are changed at will by the performer without interrupting the performance. For this purpose 15 pedals may be used which are connected with the accompanying-strings by suitable mechanism, as hereinafter described.

In the accompanying drawings, Figure 1 is a vertical longitudinal section in the plane x x' , Fig. 6. Fig. 2 is a vertical longitudinal section in the plane y y' , Fig. 6. Fig. 3 is a vertical transverse section in the plane z z' , Fig. 6. Fig. 4 is a vertical transverse section in the plane x' x ', Fig. 6. Fig. 5 is a plan view. Fig. 6 is a horizontal section in the plane y y' , Fig. 1. Fig. 7 is a vertical longitudinal section along the accompanying-strings.

Similar letters indicate corresponding parts.

The letter A indicates the side walls, which, together with the back B, the bottom C, and the 35 partition-wall B', form the casing D of the instrument. a' are the leading-strings, stretched on the sounding-board B^{IV}, in the usual manner, by hitch-pins c' and tuning-pins c'' . a'' are the accompanying-strings, stretched on the sounding-board B''' by hitch-pins d' and tuning-pins d'' . e' are the bass-strings, stretched 40 on the sounding-board B'' by means of tuning-pins e'' and hitch-pins e''' . On the bottom C of the casing is a stringer, e , on which are pivoted a row of alternating long pedals, a , and short pedals b .

e^{IV} are springs secured to the bottom C, and acting against the bottom of the pedals a b , so as to return the same to their original position after being depressed.

b' are posts fastened to the bottom C, under each of the pedals a b , allowing the pedals only a certain limited downward motion. In this row of pedals a b the long pedals a connect with the rods i back of the partition B'. The 55 rods i in turn connect with arms j , which are firmly secured to the lower series of rock-shafts k , running horizontally back of the partition B'. These rock-shafts k turn in bearings in the vertical post l , and in bearings l' , 60 secured to the partition B'.

To the rock-shafts k are secured arms n , similar to the arms j .

p p' are a set of levers pivoted to the frame q , which is secured to the casing of the instrument. The two top rows of levers p are connected with the arms n on the rock-shafts k by rods o .

s s' are another set of levers pivoted to the frame r , which is also secured to the casing D. 70 The two top rows of levers, s , are engaged by the levers p .

In the sounding-board B'' are two apertures, k'' k''' , through which pass wires t t' , provided on their upper ends with hooks t' t' , Fig. 75 3, passing over the accompanying-strings a'' , and over their lower ends are slipped spiral springs b'' , and secured to the same. The springs b'' , abutting against the piece m' , Fig. 3, keep the hooks t' t' drawn tightly on the accompanying-strings a'' . The wires t t' pass 80 through the unengaged arms of the levers s s' , and are secured to the levers by collars or nuts E. Said nuts E are firmly secured to the wires t t' , and rest on the top of the levers s s' , 85 so that when the lever-arm of one of the levers s s' is raised the corresponding hook or hooks are raised from off the corresponding accompanying-strings a'' . To each of the two top rows of levers s are attached two of these 90 wires t , operating two hooks, t' t' , in line on the corresponding accompanying - string a'' ; hence each of the two top rows of levers p , which are connected with the long pedals a and engage the upper two rows of levers s , are 95 instrumental in operating two hooks. Near each of the two apertures k'' k''' are placed bridges v w , Figs. 5 and 7, the bridge v near the aperture k'' being slightly lower than the bridge w near the aperture k''' , (see Fig. 7,) 100

while the bridge *w* is lower than the bridge *w'* at the end of the sounding-board *B''*, so that when the strings are drawn down upon the bridge *w* they will still clear the bridge *v*.
 5 The short pedals *b* connect with rods *i'* back of the partition *B'*. The rods *i'* in turn connect with arms *j'*, firmly secured at right angles to the upper horizontal series of rock-shafts, *k'*. The same turn in bearings in the 10 vertical post *l*, and in bearings *l''*, secured to the partition-wall *B*.

To the rock-shafts *k'* are secured arms *n'*, connecting with the two lower rows of levers *p'*, pivoted to the frame *q*. These levers *p'* connect with the two lower rows of levers, *s'*, of the levers *s s'*, which are connected with one wire *t* each; consequently the levers *p'*, to which are connected the short pedals *b*, are instrumental in operating one hook *t* each.
 15

20 Above the row of pedals *a b* is another row of alternating long pedals, *d*, and short pedals *e*, pivoted to the stringer *f*. To another stringer, *h*, are fastened springs *g*, pressing against the bottom of the pedals *d e*, so as to return 25 them to their original position after being depressed.

25 *b''* are posts secured to the stringer *h*, and allowing the pedals only a limited downward motion. In this row of pedals *d e* part of the 30 pedals (in the drawings the first eight are shown) connect with rods *f'*, which are connected with a series of rock-shafts, *j''*, in front of the partition *B'* by means of the arms *g'*. The rock-shafts work in bearings in the post 35 *L*, and in bearings in the piece *M*, secured to the partition *B'*.

To the rock-shafts *j''* are secured other arms, *n''*, passing through an opening, *m'''*, in the partition *B'*, back of the same, where they connect with rods *o''*, which in turn connect with levers *p''*, secured to the stringer *N*, said levers *p''* operating the hammer-action *A''*, which is made and operated in the usual manner of operating and making such actions. The hammers of the hammer-action pass through an 45 opening in the sounding-board *B''* and strike the bass-strings *e'*, as is usually done. The remaining pedals in the row *d e* are connected with rods *f''*, which connect with arms *g''*. The 50 arms *g''* are secured to a series of horizontal rock-shafts, *j''*, in front of the partition *B'*, and working in bearings in the post *L'*, and in bearings *m'''*, secured to the partition *B'*.

To the rock-shafts *j''* are secured arms *n'''* 55 at right angles to the same, and are connected with levers *p''* by rods *o'''*, the levers *p''* operating the hammers as before.

A', Fig. 3, is a pedal pivoted to the partition *B'*, and connected by a rod, *t''*, and arm 60 *u'* with a rock-shaft, *s''*, turning in a bearing, *v'*, secured to the casing, and a bearing, *v''*, secured to the top of the frame *g*. Other arms, *u''*, secured to the rock-shaft *s''*, connect with rods *w^{IV}*, which pass through the sounding-board *B'''*, and connect over the strings *a''* with

a block, *w''*, extending over any desirable number of the strings *a''*. When the pedal *A'* is depressed, the block *w''* is brought down upon the strings *a''*, forcing them on the bridge *w'''*, which bridge is lower than the bridge *v*, (see Fig. 7,) for the same reason before mentioned.
 70

In the operation of the instrument, when one of the long pedals *a* in the lower row of pedals is depressed by the foot of the player by the mechanism before described, the arm 75 of the corresponding lever, *p*, to which the rod *o* is attached, is drawn down, and the end of the lever *s* to which the wires *t t* are attached is consequently raised, and two hooks, *t t'*, are lifted from the corresponding accompanying-string *a''*, releasing the same from both bridges *v w* on the sounding-board *B'''*, lowering the pitch of the string by a whole note.
 80

When one of the short pedals *b* is depressed similarly, the arm of the corresponding lever 85 *p'*, to which the rod *o'* is attached, is drawn down, and consequently the arm of the lever *s'* to which one wire *t* is attached is raised, and one hook *t'* is lifted from the corresponding accompanying-string *a''*, releasing the same 90 from the bridge *v*, whereby the pitch of the string is lowered by one-half a note. When one of the pedals of the upper row of pedals *d e* is depressed by the mechanism before described, the hammer-action is set into motion, 95 and the corresponding bass-string *e'*, stretched over the sounding-board *B''*, is sounded. When the pedal *A'* is depressed, as before stated, the block *w''* is brought down upon the accompanying-strings *a''*, raising the pitch of the strings 100 by a whole octave. The block *w''* can extend over as many strings as may be desired. In the drawings it extends over all; but a shorter block may be used.

The instrument is played as follows: On the 105 leading-strings *a'* the melody is played with the fingers, and the pitch of the strings is changed by fingering in the usual manner. The accompanying-strings *a''* are also struck by the fingers; but the pitches of the same are 110 changed by the performer by depressing the lower pedals, *a b*. The bass-strings *e'* are struck by the hammer-action in connection with the upper row of pedals *d e*.

What we claim as new, and desire to secure 115 by Letters Patent, is—

1. In a zither, the combination of leading-strings, the pitches of which are changed by fingering in the usual manner, accompanying-strings, a series of hooks therefor for changing their pitches, and a series of pedals connected to and controlling the hooks, whereby the pitches of the accompanying-strings are under control of and changed at the will of the operator without interrupting the performance, substantially as described.
 120

2. In a zither, the combination, substantially as hereinbefore shown and described, with the accompanying-strings *a''*, of the additional bridges *v w*, the hooks *t*, the wires *t*, 125

the levers $s s'$ and $p p'$, the arms $n n'$, the rock-shafts $k k'$, arms $j j'$, rods $i i'$, and the pedals $a b$.

5. In a zither, the combination, substantially as hereinbefore shown and described, with the accompanying-strings a'' , of the additional bridge w'' , the block w'' , the rods w^{IV} , the arms u'' , the arms u' , the rod t'' , and the pedal A'.

In testimony whereof we have hereunto set to our hands and seals in the presence of two subscribing witnesses.
